[57] CLAIM

The ornamental design for a spoon display stand, substantially as shown and described.

DESCRIPTION

FIG. 1 is a top front perspective view of a spoon display stand, illustrating the left side of my new design;

FIG. 2 is a top plan view thereof;

FIG. 3 is a right side elevational view thereof;

FIG. 4 is a rear elevational view thereof;

FIG. 5 is a front elevational view thereof;

FIG. 6 is a bottom plan view thereof; and

FIG. 7 is a top, front, right side perspective view thereof; the broken line showing of the spoon being for illustrative purposes only.
